Primary Examiner — Marianne Pandozzi(74) *Attorney, Agent, or Firm* — Gregory K. Nelson**CLAIM**

The ornamental design for a container component, as shown and described.

DESCRIPTION

FIG. 1 is a front elevational view of the container component showing our new design;

FIG. 2 is a side elevational view thereof;

FIG. 3 is a top plan view thereof; and,

FIG. 4 is a bottom plan view thereof.

The broken lines in the drawings are included for purposes of illustration and form no part of the claimed design.
